UNITED STATES PATENT OFFICE.

PETER BARKER, OF ANSONIA, CONNECTICUT.

FLOAT-BALL FOR STEAM-TRAPS, &c.

SPECIFICATION forming part of Letters Patent No. 256,270, dated April 11, 1882.

Application filed February 9, 1882. (No model)

To all whom it may concern:

Be it known that I, PETER BARKER, of Ansonia, in the county of New Haven and State of Connecticut, have invented an Improved 5 Float-Ball for Steam-Traps, Water-Tanks, &c., of which the following is a specification, reference being had to the accompanying drawing.

Heretofore float-balls have generally been made by being spun of sheet-copper in hemi- 10 spheres, then lapped together and brazed at the joint; but they are apt to leak and fill with water, and also to collapse from the pressure of steam.

My invention is designed to overcome these 15 objections, and accordingly I first form a hollow ball of two united hemispheres of wood, paper, vulcanized fiber, metal, or any other suitable economical material; but wood, being light, cheap, and sufficiently strong, will serve 20 the purpose well enough. This ball forms a light, strong foundation for the final exterior casing, and I apply to it the ordinary brass nipple, screw-threaded for attachment to a suitable link or lever, and properly secured, 25 as usual. I then electroplate the ball, thus formed, with copper preferably, but any other suitable metal may be used, after which it is tinned over thoroughly. I thus produce a 30 seamless ball not liable to leak, and the internal jointed foundation, together with the outer

seamless casing, are of such strength as to prevent all danger of collapsing under pressure of steam, while at the same time light enough to float.

In addition to the improvement in the quality of my ball thus produced, it has the advantage, also, of economy of construction as compared with the metallic jointed balls usually heretofore employed. 35

In the accompanying drawing, illustrating 40 my invention, A indicates the interior jointed hollow wooden ball composed of the two hemispheres B B, suitably united and forming the foundation for the exterior thin metallic seamless casing or coating C.

D indicates the usual screw-threaded nipple, for the attachment of a suitable link or lever to be connected with an indicator. 45

The wooden ball may be covered with shellac before plating. 50

Having thus described the construction and advantages of my improved ball, what I claim, and desire to secure by Letters Patent, is—

A float-ball composed of an internal hollow foundation and an external seamless metallic 55 shell or coating, substantially as set forth.

PETER BARKER.
